UNITED STATES PATENT OFFICE.

WILLIAM H. ANDERSON, OF LOS ANGELES, CALIFORNIA, ASSIGNOR TO ECLIPSE MANUFACTURERS, INC., OF LOS ANGELES, CALIFORNIA, A CORPORATION OF CALIFORNIA.

DESIGN FOR A RADIO DIAL PLATE.

Application filed May 14, 1927. Serial No. 21,981. Term of patent 3½ years.

To all whom it may concern:

Be it known that I, WILLIAM H. ANDERSON, a citizen of the United States, residing at Los Angeles, in the county of Los Angeles and State of California, have invented a new, original, and ornamental Design for a Radio Dial Plate, of which the following is a specification, reference being had to the accompanying drawing, forming part thereof.

In the drawings:

Figure 1 is a front elevation of the radio dial plate showing my new design; and

Figure 2 is a side elevation of the radio dial plate showing my new design.

I claim:

The ornamental design for a radio dial plate, as shown.

Signed at Los Angeles, in the county of Los Angeles, State of California, this 6 day of May, 1927.

WILLIAM H. ANDERSON.
